UNITED STATES PATENT OFFICE

BRUNO LAURIS LAURSEN, OF DUNEDIN, FLORIDA, ASSIGNOR, BY MESNE ASSIGNMENTS, OF FORTY-EIGHT PER CENT TO CLEARWATER LUMBER COMPANY INCORPORATED, OF CLEARWATER, FLORIDA, A CORPORATION OF FLORIDA

FOLDING FURNITURE

Application filed April 23, 1927. Serial No. 185,970.

This invention pertains to folding furniture, particularly seats and ironing boards.

It is an object of the invention to combine a folding ironing board, a sleeve board, and a folding seat so that any of the elements of the combination may be used without interference from the others.

Another object is to produce the arrangement above described of such dimensions that it may be installed in a wall or partition between standard studding spaced sixteen inches on centers.

Another object is to so arrange the structure that no floor supports are necessary, thereby leaving the space underneath the furniture free of obstructions whenever the furniture is in operative position.

Another object is to save space by having the units in one cabinet.

Another object is to have the units self-locking so that auxiliary fasteners are not required.

Another object is to arrange the parts so that any of the units may easily be shifted from inoperative to operative position, or vice versa, by a continuous movement and by a single hand of the operator.

Another object is to utilize the back of the seat for the three-fold purpose of seat back, supporting brace for ironing board, and as part of the front of the cabinet.

Further and other objects and advantages will be hereinafter set forth in the accompanying specification and claims and shown in the drawings, which by way of illustration show what is now considered the preferred embodiment of the invention.

Fig. 1 is a front view of the cabinet when closed.

Fig. 2 is a cross-section on the line 2—2 of Fig. 1.

Fig. 3 is a view similar to Fig. 1 but with the front of the cabinet removed.

Fig. 4 is a cross-section on the line 2—2 of Fig. 1 but with ironing board and sleeve board in operative position.

Fig. 5 is a detail sectional view on the line 5—5 of Fig. 4.

Fig. 6 is a cross-section on the line 2—2

of Fig. 1 but with the seat in operative position, the ironing boards being closed in the upper part of the cabinet.

Fig. 7 is a right view of Fig. 6.

The cabinet comprises the side walls 10, base board 12, cap 14, and rear wall 16. Preferably the cabinet is of such width as to fit between studding on 16-inch centers.

When the furniture is in inoperative positions the upper half of the front of the cabinet is enclosed by door 18, carried by hinges 20. The next section of the cabinet below the door is enclosed by seat back 22, and the lower section by seat 24, connected to back 22 by a pair of hinges 26.

To move the seat from its inoperative position within the cabinet to its operative position, the user grasps handle 28 (Fig. 1) provided for the purpose and draws the seat 24 and seat back 22 to operative position as shown in Fig. 6, in which position the seat is supported from base board 12 by brace 30 hinged to board 12. The upper end of brace 30 is pivotally connected to seat rails 32 by trunnions on the ends of bar 34. The inner (rear) ends of rail 32 are supported by trunnions on the ends of bar 36 guided by grooves in walls 10. The grooves each comprise an upwardly extending straight portion 38 and a lower hooked portion 40.

The ironing board 42 and sleeve board 44 are shown in operative position in Fig. 4. The inner end of board 42 is provided at its under side with a cross bar 46 having trunnions 48 on its ends, which enter slots in cabinet side members 10. Each slot has a vertical section 50 and a short upper section 52 projecting forwardly from the upper end of section 50. In operative position trunnions 48 are in sections 52. Board 42 is also supported at a point midway of its length by seat back 22 which acts as an angle brace to support board 42 on the upper edge of seat 24 through hinges 26 (Fig. 4). The upper edge of back 22 is provided on its rear with a transverse strip 54 having trunnions 56 on its ends engaging slots 58 in longitudinal rails 60 on the under side of board 42 near the outer edges thereof.

The outer ends of slots 58 are so located that board 42 is held level by trunnions 56. It is evident from Fig. 4 that the weight of board 42, plus the weight and pressure of an iron thereon, acts to hold it in operative position without the use of fasteners of any kind.

Sleeve board 44 is also shown in operative position in Fig. 4. This board is bifurcated at its inner end to form arms 62. Each arm 62 is attached at its inner end by a hinge 64 to a cross bar 66 fast to rear wall 16 of the cabinet. Freely suspended between arms 62 on hinge wire 68 is a block 70 of proper length to support board 44 horizontally when block 70 rests on board 42 as in Fig. 4.

If sleeve board 44 is not wanted for use it is swung upwardly on hinge 64 until it rests against the rear wall of the cabinet as shown in Figs. 2 and 6. When board 44 is moved to this position, block 70 remains vertical and hangs between the arms 62, against the rear wall of the cabinet.

If ironing board 42 is not wanted for use the operator grasps its free outer end and pushes inwardly and upwardly, with the result that trunnions 48 are moved out of horizontal groove 52 and downwardly in groove 50 to the lower end thereof, at the same time trunnions 56 move along grooves 58 and the board takes the position shown in Figs. 2 and 6, standing vertically in front of sleeve board 44 in the upper portion of the cabinet. That portion of the cabinet may then be enclosed by shutting door 18.

If boards 42 and 44 are both in operative position, they may both be folded back into the cabinet by the single movement above described for board 42 alone. Boards 42 and 44 will remain in inoperative position without use of fasteners because when they are vertical their centers of gravity are to the rear of their points of support, which are trunnions 48 and hinges 64 respectively.

When seat 24 is moved to its inoperative position as described in the copending application above mentioned, it takes the position shown in Fig. 2, thereby forming an enclosing front for the lower part of the cabinet. When the seat is closed, trunnions 56 at the top of seat back 22 move along grooves 58 and back 22 assumes the position shown in Fig. 2, wherein it forms the front enclosure of the cabinet for the space between the bottom of door 18 and top of seat 24.

It is to be understood that the invention is not limited to the construction herein specifically illustrated but can be embodied in other forms without departure from its spirit.

I claim—

1. In a structure of the character described, in combination, upright side walls

having lower and upper grooves in the inner surfaces thereof, each lower groove having an upright inclined portion and an upwardly and forwardly inclined portion at the lower end of the upright portion, and each upper groove having an upright portion and a forwardly extending portion at the lower end of said upright portion, a seat having trunnions disposed and movable in the lower grooves of said side walls, an ironing board having trunnions disposed and movable in the upper grooves of said walls and also having a grooved portion at its underside, and a seat back and ironing-board brace hingedly connected to the seat and having trunnion means disposed and movable in the grooved portion of the ironing board, whereby the seat, ironing board and seat back may be supported in operative and inoperative positions at the will of the operator and may be moved from either of said positions to the other by a single continuous operation.

2. In a structure of the character described, in combination, upright side walls having lower and upper grooves in the inner surfaces thereof, each lower groove having an upright inclined portion and an upwardly and forwardly inclined portion at the lower end of the upright portion, and each upper groove having an upright portion and a forwardly extending portion at the lower end of said upright portion, a seat having trunnions disposed and movable in the lower grooves of said side walls, an ironing board having trunnions disposed and movable in the upper grooves of said walls and also having a grooved portion at its underside, and a seat back and ironing-board brace hingedly connected to the seat and having trunnion means disposed and movable in the grooved portion of the ironing board, whereby the seat, ironing board and seat back may be supported in operative and inoperative positions at the will of the operator and may be moved from either of said positions to the other by a single continuous operation; the seat and seat back being of an area to close a portion of the space between the side walls when said seat and back and ironing board are in inoperative position.

In testimony whereof I hereto affix my signature.

BRUNO LAURIS LAURSEN. 120
